UNITED STATES PATENT OFFICE.

ROBERT McCULLY, OF PHILADELPHIA, PENNSYLVANIA.

GRINDING-MILL.

SPECIFICATION forming part of Letters Patent No. 274,210, dated March 20, 1883.

Application filed July 27, 1882. (No model.)

To all whom it may concern:

Be it known that I, ROBERT McCULLY, a citizen of the United States, and a resident of the city and county of Philadelphia, in the State of Pennsylvania, have invented certain new and useful Improvements in Grinding - Mills, of which the following is a specification, reference being had to the accompanying drawings, wherein—

10 Figure 1 is a plan, partly sectional, of a grinding-mill embodying my invention. Fig. 2 is a side elevation of same. Fig. 3 is a longitudinal section of shaft - bearing. Fig. 4 is a detail plan of part of the same. Fig. 5 is a transverse vertical section of the mill, partly in elevation. Fig. 6 is a detail plan of friction-rollers and frame therefor. Fig. 7 is an end view of disk with automatic feed, the latter being in section. Fig. 8 is a broken elevation of same. Fig. 9 is a broken perspective of same. Fig. 10 is a plan of modified arrangement of friction-rollers, and Fig. 11 is a detail section of modification of bearing for roller-frame.

15 My invention has relation to that class of grinding-mills in which the grinding-disks are mounted upon separate and relatively - eccentric shafts in such manner that a portion of one grinding-disk overlaps a part of the other disk, said disks being so arranged that they 20 are closed, or nearly so, from their centers toward the peripheries of their lower parts and opened from their centers toward their top edges to receive the feed.

25 Heretofore such mills have been so constructed as to have the grinding-disks pressed or caused to come together by means of appliances which exerted a pressure in the line of or on the shafts upon which said disks were mounted. Such construction not only results 30 in a waste of power, owing to the undue friction produced by the lateral straining of the driving-shafts and pedestals and the positive friction caused by the pressure of the step-bearing against the ends of said shafts, but is 35 also open to the objection that the pressure intended to be exerted upon the grinding-disks is not directly applied to that part of the disks which effect the grinding.

40 My invention has for its object to avoid such 45 objection by so constructing the mill that the mill or driving-shafts are perfectly free of lat-

eral strain and end-pressure; and the grinding-disks are provided with appliances for exerting or supporting any desired pressure required upon the parts of the disks between 55 which the grinding operation takes place.

To this end my invention consists in the novel construction, combination, and arrangement of parts having especial reference to the provision of two movable frames located back 60 of the grinding-disks. Between said disks and frames are placed anti-friction - rollers, said frames forming bearings for the driving-shafts, and are provided with mechanism for adjusting the frames toward the grinding-disks to 65 exert any desired pressure upon them, to take up the wear of their grinding - surfaces, and also to vary the grade of grinding of the disks.

Referring to the accompanying drawings, A represents the main frame of the machine; B 70 and B', the grinding-disks, mounted on separate shafts, C and C', respectively, which are out of line with one another, as shown, so that the disks overlap each other about one-half of their grinding faces b b. The latter are made 75 separate from said disks, but secured thereto by screw-bolts b' b'. The rear side, b², of each disk is formed with a peripheral flange, b³, and an annular projecting ring, b⁴, the face of which is inclined, as shown. 80

D and D' are frames having grooved ends d, adapted to rest upon and slide on the tongue bars or blocks E and E', secured to the frame of the mill. Said grooves and tongues may, if desired, be formed as shown in Fig. 5, so as to 85 interlock with each other to permit the frames D and D' to serve as connecting-bars for bracing the frame A at its center. The frames D and D' have annular flanges d' on their front faces, also annular rings d², the faces of which 90 have an inclination corresponding to that of rings b⁴ of the disks. Said frames are provided with bearings d³ d⁴ for the forward ends of the shafts C C'. The rings b⁴ d² form seats or ways 95 for the anti-friction rollers f f in annular frames F F, which have central openings, f' f', and are mounted upon the hubs d⁴ of the disks and of the frames, as shown in Fig. 1.

G G' represent nuts having threaded openings g g. Said nuts are rigidly secured to the 100 frames D D' by screws or bolts g' g'. Into said nuts pass the rods H H', threaded at h h. The

end h' of rod H' is seated upon a block secured to a brace, M' , and is provided with a retaining-collar, h^2 , and an angular collar, h^3 , to which a wrench is applied for turning rod H' , to adjust frame D' to and from disk B' . The screw-rod H also has an angular collar or end, h^3 , for like purposes. Said rod is shown as passing through brace M , in order that a spring, L , may be placed thereon between brace M and nut h^4 to afford a spring-support for said rod H . If desired, said spring may be dispensed with; or both screw-rods $H H'$ may be provided with a spring.

$N N$ represent collars secured to shafts c and c' , immediately to the rear of frames D and D' , as shown in Fig. 1. Said collars hold the disks B and B' back against the friction-rollers $f f$, so that the grinding-surfaces of the disks will be under full control of screw-rods $H H'$, and all irregular movement of the grinding-disks to and from each other is avoided. The rear ends of shafts $C C'$ have their bearings in the pillow-blocks $O O$, secured to frame A , and $P P$ are driving-pulleys for said shafts.

It will be noticed that the screw-rods $H H'$ are substantially in line with each other and with the overlapping portions of the grinding-disks, and the latter are supported on each side of the shafts by the frames $D D'$. Hence as the screw-rods $H H'$ are turned to cause the frames to move toward each other a pressure is exerted upon the grinding-disks, which is equally distributed over the entire area of said disks. The extent of such pressure may be varied by increasing or diminishing the adjustment of the screw-rods $H H'$. The disks $B B'$ being supported on each side of their respective shafts and rolling on the friction-rollers $f f$, all lateral strain on shafts $C C'$ is avoided. The provision of frames $D D'$ and screw-rods $H H'$ dispenses with the necessity of end-pressure on said shafts. Hence power applied to the latter exerts almost its entire force upon the grinding, and a large portion thereof is not used up or wasted in overcoming the friction of the lateral strain and end pressure of the driving-shafts, as has heretofore been the case.

To adjust the disks in relation to each other so that the bottom of their overlapped parts shall be but slightly separated from each other while their upper parts are divergent for the introduction of a hopper or the feed, I provide the following instrumentalities, which may or may not be employed, their use depending upon the nature, amount, and size of the material to be ground.

If desired, the mill may be so constructed that the disks have a movement to and from each other only; or they may have a lateral and vertical movement in addition thereto. In the latter case the shafts $C C'$ and frames $D D'$ are secured in or placed upon the secondary frames $A' A'$, pivoted at a to main frame A . The frames A' have slotted ends a^2 for the

passage of set-screws a^3 . When the latter are loosened the frames A' may be raised or lowered to skew the shafts $C C'$ from a horizontal plane, causing the lower parts of the disks to come together while their upper parts recede from each other. To provide for a lateral adjustment of the disks and shafts, the tongue-blocks E are slotted at $e e$ for passage of screws e' , and are centrally pivoted at e^2 to frames A' . The pillow-blocks O are constructed, as shown in Figs. 3 and 4, so that when the set-screws o are loosened said blocks have liberty of lateral movement on the plate o^2 , by reason of the screws which connect said blocks O to plates o^2 moving in the slots in said plates, said screws and slots being more plainly shown in Figs. 3 and 4. The plates o^2 are secured by bolts o^3 to frames A' . When the screws, o , are loosened the frames $D D'$ and shafts may be moved laterally, and the blocks E and O turn upon their pivotal connections to adjust themselves to the movement of said frames and shafts, whereupon the set-screws o are tightened up to hold the pillow-blocks in a fixed position to maintain such lateral adjustment.

If desired, the friction-roller-sustaining frames F may be dispensed with and the rollers held in place between the disks and frames by means of bearings formed integrally with the disks or with the frames. So, too, instead of employing a wrench or similar implement to effect adjustment of rods $H H'$ they may be provided with worm-and-gear mechanism for accomplishing such result.

In Fig. 10 I have shown the friction-rollers f as being formed without journals at their ends, and in rolling contact with each other.

In Fig. 11 I have illustrated a modified form of bearing for the roller frame F , wherein friction-rollers f^4 are interposed between the frame and its bearing F' . The latter is formed on the frame D , as shown, and is in the shape of an annular flange cast integral with or secured to said frame. Such construction removes the weight of the frame F and its rollers from the driving-shaft, and allows it to fall wholly upon the frame D .

In Figs. 7, 8, and 9 I have indicated a construction of an automatic feed for the mill, consisting of a comb or serrated valve, R , adjustably secured to shaft R' by set-screw r . The shaft R' has its bearings secured to hopper R^2 , as shown at $r' r'$, and is provided with a slotted arm or crank, R^3 , adjustably secured to another like arm or crank, S , by means of set-screw s . The crank S is secured to shaft T , the bearing t for which is screwed to the frame of the machine or mill, as shown at t' . Upon the opposite end of shaft T is located a double-end tripper, T' , which is in line with a cam, T^2 , on disk B . As the latter revolves the cam T^2 trips each end of the tripper T' to oscillate the shafts T and R' , which in turn vibrates the valve R in the hopper-tube. As the valve R so moves, the ore or other ma-

terial to be ground passes between its combs and falls down between the grinding-disks. By adjusting the height of said valve within the hopper and altering the angle of inclination or connection of the cranks R⁴ and S, the feed is varied as desired.

5 The spring L (shown in Fig. 1) may be arranged as illustrated at X, Sheet 1, wherein said spring is designed to be compressed by means of the bolts l' l and plate l. By such arrangement any desired spring-pressure may be obtained for the frame D. By screwing up or unloosening the nuts on bolts l' l the spring is compressed or allowed to expand. Hence a 10 positive and speedy regulation of spring-pressure is secured.

What I claim as my invention is—

1. The combination of grinding-disks B B', their relatively-eccentricsbafts C C', the frames 20 D D', and anti-friction rollers interposed between said disks and frames, substantially as shown and described.

2. In a grinding-mill, the combination of 25 two disks or plates, separate and relatively-eccentric shafts on which said disks are mounted, a frame or carriage back of each disk, having a bearing for one of said shafts, and friction-rollers interposed between said frames and disks, substantially as shown and described.

3. In a grinding-mill, the combination of 30 two plates or disks, relatively-eccentric shafts on which said disks are mounted, mechanism, substantially as shown and described, for moving said disks and shafts vertically and laterally, as set forth.

35 4. The combination of a frame, A, blocks E E', the frames D D', having bearings d³ d³, the shafts C C' out of line with each other, the bearings O, disks B B', and friction-rollers f, substantially as shown and described.

40 5. The combination of disks B B', shafts C C', frames D D', having bearings d³ d³, mechanism for moving said frames toward said disks, and anti-friction rollers interposed between the disks and frames, substantially as shown and described.

45 6. The combination of disks B B', shafts C C', friction-rollers f f, frames D D', having bearings d³, and adjusting mechanism interposed between said frames D D' and the mill-frame, substantially as shown and described.

50 7. The combination of disks B B', shafts C C', friction-rollers f f, the frames D D', having bearings d³ d³, and collars N N, substantially as shown and described.

55 8. The combination of frame A, secondary frames A' A', adapted to be moved vertically, the shafts C C', having bearings O O, the frames D D', having bearings d³, and adjust-

ing mechanism H H', friction-rollers f f, and 60 disks B B', substantially as shown and described.

9. In a grinding-mill, the combination of two grinding disks or plates, relatively-eccentric shafts, on which said plates are mounted, 65 friction-rollers f f, sliding frames D D', and blocks E E', substantially as shown and described.

10. In a grinding-mill, the combination, with 70 disks B B' and shafts C C', the frames D D', having bearings d³ d³ and slotted ends d, and the blocks E E', secured to the frame of the mill, substantially as shown and described.

11. In combination with the disks and shafts 75 of a grinding-mill, the frame D, having slotted ends d d, shaft-bearing d³, nut G, and adjusting mechanism therefor, substantially as shown and described.

12. In combination with a grinding-disk, the 80 flange b³, ring or seat b⁴, anti-friction rollers f f, frames D, and adjusting mechanism H, substantially as shown and described.

13. The combination of disks B B', the shafts C C', frames D D', friction-rollers f f, and screw-rods H H', substantially as shown and 85 described.

14. The combination of disks B B', shafts C C', friction-rollers f f, frames D D', bearings O, plates o², screws o, and the adjustable blocks E', substantially as shown and described. 90

15. In a grinding-mill, the combination of 95 grinding-disks, friction-rollers, supporting-frames therefor, and mechanism for adjusting said frames to and from said disks, substantially as shown and described.

16. In a grinding-mill, the combination of 100 grinding-disks, friction-rollers, supporting-frames therefor, and mechanism for moving said frames to and from said disks and moving them laterally, substantially as shown and described.

17. In a grinding-mill, the combination of 105 two plates or disks out of center with each other, an automatic feed therefor, adjustable frames, and friction-rollers back of said disks, and mechanism for adjusting said frames, substantially as shown and described.

18. The combination, with grinding-disk B, of anti-friction rollers f f, frame D, nut G, screw-rod H, spring L, brace or rod M, plate 110 l, and bolts l' l', substantially as shown, and for the purpose set forth.

In testimony whereof I affix my signature in the presence of two witnesses.

ROBERT McCULLY.
